(57) **CLAIM**

The ornamental design for a fascia tissue treatment device with a row of treatment elements, as shown and described.

DESCRIPTION

FIG. 1 is a front perspective view of a fascia tissue treatment device with a row of treatment elements;

FIG. 2 is a front elevational view of the device of FIG. 1; FIG. 3 is a rear elevational view of the device of FIG. 1; FIG. 4 is a right-side elevational view of the device of FIG. 1;

FIG. 5 is a left-side elevational view of the device of FIG. 1;

FIG. 6 is a top view of the device of FIG. 1; and,

FIG. 7 is a bottom view of the device of FIG. 1.

The broken lines are for the purpose of illustrating unclaimed structure, and form no part of the claimed design.

1 Claim, 3 Drawing Sheets
